US0D1083351S

(12) **United States Design Patent** (10) **Patent No.:** **US D1,083,351 S**
(45) **Date of Patent:** **** Jul. 15, 2025**

(54) **UMBRELLA**

(71) Applicant: **Dougan H. Clarke**, Miami, FL (US)

(72) Inventor: **Dougan H. Clarke**, Miami, FL (US)

(**) Term: **15 Years**

(21) Appl. No.: **29/901,584**

(22) Filed: **Sep. 1, 2023**

(51) LOC (15) Cl. **03-03**

(52) U.S. Cl.

USPC **D3/5**

(57) **CLAIM**

The ornamental design for an umbrella as shown and described.

DESCRIPTION

FIG. 1 is a perspective view illustrating my design for an umbrella;

FIG. 2 is a top view thereof;

FIG. 3 is a bottom view thereof;

FIG. 4 is a front view thereof, the back view being a mirror image of same;

FIG. 5 is a left side view thereof; and,

FIG. 6 is a right side view thereof.

The broken lines show portions of the umbrella that form no part of the claimed design.

1 Claim, 6 Drawing Sheets
